TWO CYCLE INTERNAL COMBUSTION
ENGINE

Harry Ralph Ricardo, London, England

Application May 22, 1940, Serial No. 336,669
In Great Britain April 10, 1940

3 Claims. (Cl. 123—72)

This invention relates to high speed two-stroke internal combustion engines operating with compression ignition having in the head of the cylinder a combustion chamber with a fuel injector therein and into which substantially the whole of the air charge is forced at the end of the compression stroke of the working piston, this air charge having been delivered into the cylinder through ports in the wall thereof by a pump of the displacement type. The object of the invention is to avoid undesirable accelerations in the valve-operating mechanism while attaining a determined relation between the times of closing of the exhaust port and closing of the air inlet ports.

According to this invention there is an exhaust port in the inner wall of the combustion chamber in the head of the cylinder and this port is controlled by a poppet valve which is "masked", that is to say the valve and its seat in the port are respectively formed and arranged so that after the valve is first lifted off its seat it must move a determined distance before the port is effectively opened for the outflow of the exhaust gases and similarly when returning to its seat the valve will move a determined distance after the port is closed. A pump comprising a cylinder and piston reciprocating therein delivers air through a transfer passage controlled by a valve to the ports in the cylinder wall and the "masked" exhaust valve is mechanically actuated in such timed relation to the movements of the working piston that the exhaust port will be closed before the air inlet ports are covered by the working piston on its instroke and before the air pump piston has completed its inward stroke. Consequently after closing of the exhaust port air will continue to be delivered by the pump into the working cylinder through the ports in the wall of the latter thus causing a rise in pressure in the cylinder. To effect this the pump piston is driven from the crankshaft and reciprocates out of phase with the working piston. With regard to the "masking" of the exhaust valve this is arranged so that the valve will move a distance which is between one-sixth and one-twelfth of the total lift of the valve before the port is effectively opened and similarly after the port has been closed. The exhaust port with the "masked" valve therein is centrally positioned in the combustion chamber whose contour is a figure of revolution about an axis coincident with the cylinder axis. This chamber is in open communication with the cylinder through a "mouth" whose diameter is less than the maximum diameter of the combustion chamber but is greater than the diameter of the exhaust valve.

With the above-mentioned construction it is possible to operate a high speed two-stroke internal combustion engine of the type indicated

according to a method in which the outflow of exhaust gases through an exhaust port in the head of the cylinder ceases before the air inlet ports in the wall of the cylinder are closed thus increasing by the continued action of the pump which supplies the air the pressure of the air charge in the cylinder at an early stage in the compression stroke of the working piston. In operating an engine according to this method and as a result of the exhaust port being controlled by a "masked" valve and by employing suitable timing, there is obtained an efficient scavenging first by the rapid opening of the exhaust port due to the "masking" of the valve and secondly by the inflow of air when the scavenge air inlet ports are uncovered this air having been locked up under pressure in the scavenge air belt from which these ports lead.

As a result of the "masking" of the exhaust valve the longer period available for the operation of the total movement that must be imparted to this valve enables more gradual accelerations and decelerations to be provided in the valve-actuating mechanism than would be the case in a similar high speed engine if an unmasked valve were used. In a two-stroke engine of this type operating at high speed the period during which the valve is open is necessarily very short as compared with the valve movements in an engine operating on the four-stroke cycle and at a similar speed. Further, in such a two-stroke engine free egress of the exhaust gases is of vital importance for efficiency so that an adequate valve lift must be provided.

Excessive accelerations and decelerations are difficult to achieve satisfactorily and place considerable stress on the valve gear being apt to cause valve bounce and other troubles. Hence the "masking" of the exhaust valve in the head of the cylinder is an important factor in operating the engine according to the method set out above, this feature being necessarily associated with the timing of the valve and the movements of the working piston and pump piston respectively and in relation to each other.

The accompanying drawings illustrate by way of example the principal features of a high speed two-stroke engine of the kind referred to and also in some detail arrangements of the "masked" exhaust valve in the combustion chamber in the head of the cylinder. In these drawings—

Figure 1 is a sectional elevation of the improved engine showing the working cylinder, crankshaft and pump cylinder, the section being taken normal to the crankshaft axis and through the axes of the working and pump cylinders.

Figure 2 is a longitudinal section through the rotary valve which controls the air flow through the transfer passage between the pump cylinder and the working cylinder. This section is taken

on the line 2—2 in Figure 3 looking in the direction of the arrow.

Figure 3 is a sectional end elevation showing part of the mechanism by which the exhaust valve, the rotary valve and the fuel pump are operated from the crankshaft.

Figure 4 is a transverse section on the line 4—4 in Figure 1 showing the scavenging air belt and inlet ports in the wall of the cylinder.

Figure 5 is a sectional elevation on an enlarged scale of the combustion chamber in the head of the cylinder and the "masked" exhaust valve and port in that chamber, the valve being shown lifted off its seat.

Figure 6 is a view similar to Figure 5 showing an alternative construction of the combustion chamber.

Referring more particularly to Figures 1, 2 and 3 the cylinder A is conveniently provided with a liner B in which are formed the ports B¹ through which scavenging air enters the cylinder when these ports are uncovered by the piston C. The head D of the cylinder may be detachable and in it is a combustion chamber E of the "open" type, that is to say, the chamber communicates with the end of the cylinder by way of a "mouth" of substantial diameter. This combustion chamber E is centrally situated with respect to the axis of the cylinder A and the contour of this chamber is a figure of revolution about this axis. Centrally situated in the inner wall of this chamber is an exhaust port F in which is seated an exhaust valve G the detailed construction of this valve and its seat in the port F being more particularly described hereunder and illustrated on an enlarged scale in Figures 5 and 6. The exhaust port F opens into the exhaust manifold F¹. The exhaust valve G is operated by the camshaft G¹.

Scavenging air is delivered into the cylinder through the ports B¹ from a pump comprising a cylinder H in which is a piston H¹ reciprocated by a link H² which connects the piston to the big end of the connecting rod C¹. The axis of the pump cylinder H is arranged at right angles to the axis of the crankshaft J but conveniently the pump cylinder axis is in a horizontal plane which lies below the horizontal plane which contains the crankshaft axis. With this arrangement the pump piston H¹ will be reciprocated out of phase with the working piston C. The air from the pump cylinder H is delivered through a transfer passage K to a scavenging air belt K¹ surrounding the ports B¹. In the end of the transfer passage K adjacent to the pump cylinder H is a rotary valve L which controls not only the delivery of air from the pump into the transfer passage but also the inlet of air to the pump cylinder.

The construction and arrangement of the rotary valve L is also shown in Figure 2. The valve L lies within a ported liner M and the valve is mounted on a shaft L¹ on one end of which is a crank pin L². The valve itself cooperates with ports M¹, M² in the liner M these ports communicating respectively with the pump cylinder H and the transfer passage K. There is also a communication with the main air inlet N. In the valve itself the part L³, as seen in Figure 2, controls the delivery of air from the pump into the transfer passage K. Parts L⁴ control the suction through the inlet N to the pump.

Referring now to Figure 3, this shows the linkage by means of which the camshaft G¹, the shaft L¹ of the valve L and certain other aux-

iliaries are driven from the crankshaft J. On the end of the crankshaft is an eccentric J¹ which engages a bearing in a cross-shaped four-armed link. One arm O of this link extends upwardly and engages a crank pin G² on the end of the camshaft G¹. The horizontally extending cam O¹ of this link engages the crank pin L² on the end of the shaft L¹ which carries the rotary valve L. The second and oppositely extending horizontal arm O² of the link engages a crank pin P on a shaft which actuates the fuel pump P¹ and conveniently also a dynamo. The fourth downwardly directed arm O³ drives through a crank pin Q an oil pump situated in the engine sump.

The crank pin L² on the end of the shaft L¹ conveniently serves also to drive through a drag link a water-circulating pump R as seen in Figure 2.

The air inlet ports B¹ in the wall of the cylinder liner B are preferably arranged tangentially in the manner shown in the cross-section in Figure 4.

Referring now to Figure 5 which shows on an enlarged scale the detailed construction of the exhaust valve G and its seat in the port F, the valve seat F² is arranged at the bottom of a cylindrical recess F³ of suitable depth. The valve itself has a cylindrical part G³ adapted to engage this recess F³ and having substantially the same depth. The conical part G⁴ of the valve which engages the seat F² lies beyond this cylindrical part G³. This arrangement is known as "masking" of the valve, the effect being that both during the initial opening movement and during the final closing movement of the valve, the flow of gas through the port F is prevented.

With this arrangement the valve-operating mechanism can be constructed so as to cause lifting of the valve to commence before the exhaust gases are actually permitted to pass out through the port, while similarly the port is in effect closed before the valve has actually come down on to its seat. There is therefore a longer period available for the operation of the valve with the result that the accelerations and decelerations involved in the actuation of the valve by the cam can be more gradual than if the same actual effective period of opening of the valve were to be obtained with an unmasked valve. In order to determine the extent of "masking" requisite, it may be said that taking engine speed and multiplying this by the valve lift, then the greater the product thus obtained so much deeper should be the masking, that is to say, the depth of the cylindrical recess F³ in the port.

In a high speed two-stroke engine of the kind to which the present invention relates the angular period during which the exhaust valve is open is very short as compared with the time during which the exhaust valve is open in an engine operating on the four-stroke cycle at the same speed or even when such an engine is running at a slower speed. Further free egress of the exhaust gases is of vital importance for the efficiency of a two-stroke engine of the kind referred to so that an adequate valve lift is required. This masking of the valve enables an adequate valve lift to be provided and the valve to be opened and closed in the short interval necessary in a high speed engine while avoiding the disadvantages of excessive accelerations and decelerations which in practice it is not easy to achieve satisfactorily and which place con-

siderable stress on the valve gear and are apt to lead to various troubles.

The employment of masked inlet valves for internal combustion engines has been proposed by the present inventor and also by others. In the present invention, however, not only is this masking utilised on an exhaust valve, but in an engine, namely a two-stroke high speed internal combustion engine operating with compression ignition, a particular type which had not been evolved when the present inventor and others proposed the use of masked inlet valves. It may be said therefore that the advantages accruing from the use of a masked exhaust valve are peculiar to such a valve when used in an engine of the particular type indicated.

In the present instance the masked exhaust valve is combined with an engine having the features described above in which by means of the link member O, O¹, O², O³ the exhaust valve G and the rotary valve L are operated in timed relation to each other and to the working piston C and the pump piston H¹, with the result that the exhaust port F will be closed before the air inlet ports B¹ are covered by the working piston C on its instroke and before the air pump piston H¹ has completed its inward stroke. As air thus continues to be delivered into the cylinder after closing of the exhaust port the air pressure in the cylinder is increased above that of the normal scavenging air pressure at the beginning of the compression stroke of the working piston.

It is to be noted further that owing to the timing of the rotary valve L air continues to be delivered by the pump into the transfer passage K and air belt K¹ after the ports B¹ have been closed by the piston C. This results in air under some pressure being locked up in the transfer passage K and the air belt K¹ so that when on the outstroke of the piston C the ports B¹ are uncovered and at the same time the exhaust port F is rapidly opened owing to the masking of the exhaust valve, air under pressure will at once enter the cylinder and cause an efficient commencement of the scavenging period which is continued by the delivery of air from the pump.

The combustion chamber E is conveniently formed as shown in Figure 5, being provided around its mouth which opens into the end of the cylinder with a lip constituted by an inserted ring E¹ which is at least to some extent heat-insulated in that it is merely held in place by the screwed-in ring E². A slight protrusion C¹ on the face of the piston C enters the lipped mouth at the end of the compression stroke.

It will be seen from Figure 5 that the combustion chamber E which, as mentioned above, is a figure of revolution about the cylinder axis, has a maximum diameter greater than the diameter of its mouth measured inside the lip member E¹. The diameter of this mouth however is slightly greater than the diameter of the valve G. This allows for the insertion of the valve. The fuel injector is arranged to deliver the fuel spray into the chamber E through its side wall.

The extent to which the valve should move after it has left its seat and before the effective opening of the port, and similarly the distance through which the valve must move after the port has in effect been closed and until the valve 70 is seated, should be of the order of from one-

sixth to one-twelfth of the total lift of the valve.

Figure 6 shows an alternative construction of the combustion chamber. In this instance this chamber E³ is substantially cylindrical with the masked exhaust port F centrally situated in the inner wall. In this instance the combustion chamber E³ is in effect a recess of suitable dimensions formed in the water-cooled head of the cylinder. The fuel injector S is conveniently arranged substantially as shown in this figure.

What I claim as my invention and desire to secure by Letters Patent is:

1. In an internal combustion engine operating with compression ignition the combination of a cylinder, a combustion chamber in the head of the cylinder with a fuel injector therein into which chamber substantially the whole of the air charge is forced at the end of the compression stroke by the piston in the cylinder, an exhaust port centrally situated in the inner wall of the said combustion chamber with a poppet valve seated in this port the valve seat in this port being set in a cylindrical recess and the valve having a corresponding cylindrical part, an air pump comprising a cylinder and a piston reciprocated therein directly from the engine crankshaft, the pump cylinder being mounted on the crankshaft casing with the axis of that cylinder substantially at right angles to the axes of the working cylinder and of the crankshaft, air inlet ports in the wall of the working cylinder and controlled by the piston therein, a transfer passage between the pump cylinder and said air inlet ports with a valve in this passage adjacent to the pump cylinder, and mechanism operated by the engine crankshaft and actuating said exhaust valve and said valve in the transfer passage in timed relation with the working piston and the pump piston as set forth.

2. A method of operating a high speed two-stroke internal combustion engine of the type indicated, according to which the operation of a "masked" valve in an exhaust port in the head of the cylinder is timed in relation to the movements of the working piston and of a displacement pump, which operates out of phase with the working piston, with its delivery of air to ports in the wall of the cylinder controlled by a rotary valve, so that by reason of the "masking" of the valve a rapid opening and closing of the exhaust port is obtained and the exhaust port is closed before the air inlet ports in the wall of the cylinder are covered on the instroke of the piston, when by the action of the pump air continues to be supplied raising the pressure of the air charge in the cylinder at an early stage in the compression stroke of the working piston, and finally when on the outstroke of the piston the air inlet ports are uncovered air under a pressure above that of the atmosphere will at once enter the cylinder as set forth.

3. The construction of internal combustion engine set out in claim 1 in which the recess around the valve seat has a depth in relation to the total lift of the valve which necessitates a movement of the valve of from one-sixth to one-twelfth of its total lift before the port is effectively opened and a similar distance after the port has been closed.

HARRY RALPH RICARDO.
